GLASS GRINDING MACHINE

Henry O. Kranich, Toledo, Ohio, assignor to
Libbey-Owens-Ford Glass Company, Toledo,
Ohio, a corporation of Ohio

Application October 2, 1930. Serial No. 486,105

10 Claims. (Cl. 51—74)

This invention relates broadly to glass grinding machines and is more particularly directed to improvements in that type of grinding machine commonly known as the Weber edging machine as exemplified in Patent No. 1,680,920, issued August 14, 1928, wherein the edges of a plurality of glass sheets are simultaneously ground and polished by supporting them in a substantially vertical position and passing them in a definite substantially horizontal path continuously over and in engagement with a series of rotatable grinding and polishing elements in the form of grooved wheels. In this specification, the term "glass" is used in its generic sense 15 to designate either plate glass, laminated glass, or substances of similar characteristics.

The general object of the present invention is the provision of novel means cooperating with the grinding and polishing wheels for maintaining the glass sheets in a vertical position during the surfacing thereof and for also holding the edges of said sheets in proper engagement with said surfacing elements.

Another object of the invention is the provision of means of the above character, easily and quickly adjustable in order to accommodate sheets of various sizes and also wherein the pressure exerted upon the sheets to hold them in engagement with the grinding and polishing elements may be varied as desired.

Other objects and advantages of the invention will become more apparent during the course of the following description when taken in connection with the accompanying drawings.

35 In the drawings forming a part of this application and wherein like numerals are employed to designate like parts throughout the same,

Fig. 1 is a side elevation, partially broken away, of a glass grinding machine constructed in accordance with the present invention,

Fig. 2 is a vertical section taken substantially on line 2—2 of Fig. 1, and

Fig. 3 is a detail section of the sheet positioning and holding means taken substantially on line 3—3 of Fig. 1.

There has been illustrated in the drawings and will therefore be described herein only those portions of a Weber edge grinding machine which are necessary to a complete understanding of the present invention; and for a more specific disclosure of this type of machine attention is directed to the patent mentioned above.

The glass grinding machine herein provided is preferably constructed of a plurality of unit sections A, B, etc. removably secured to one an-

other end to end so that any desired number of sections may be used dependent upon the number of grinding and/or polishing elements the work requires. Each unit section is composed of end members 5 and 6 connected by 60 longitudinally extending braces 7, to which frame members the runway supports 8 are secured. Carried by the runway supports 8 are channel irons 9, the upper edges of the side portions of which constitute guide rails along which the 65 pusher blocks 10 are slid. The pusher blocks 10 are provided with a plurality of slots within which the glass sheets 11 fit. As pointed out above, the pusher blocks slide along upon the channel irons and are moved forwardly to advance the sheets by means of an endless sprocket chain 12 which engages lugs 13 on the pusher blocks.

Each unit section A, B, etc. is provided with a sub-frame 14 carrying spaced bearings 15 with- 75 in which is journaled a transverse shaft 16 to the front end of which is secured a grinding or polishing wheel 17 driven in any preferred manner such as by means of belts 18 and pulleys 19 mounted upon shaft 16. The surfacing wheel is 80 provided with a plurality of grooves 20 in its periphery as best shown in Fig. 2 and the lower portion of said wheel operates within a receptacle 21 which is adapted to contain a suitable grinding or polishing medium, while the upper 85 portion of the wheel projects upwardly through a slot in the bottom of channel irons 9.

Positioned within the channel irons 9 between adjacent surfacing wheels 17 are supporting runways 22, each runway being grooved as at 23 90 so that the grooves 23 align with and form an extension of the grooves formed in the surfacing elements. The runways 22 cooperate with the grinding and polishing elements to support the sheets during the surfacing thereof and further 95 serve to support said sheets during their travel from one surfacing element to the next.

According to the present invention, there is carried by each unit section opposite each grinding and polishing wheel 17 a vertically disposed 100 supporting arm or standard 24 preferably in the form of a channel iron. This channel iron is provided with a vertical slot 25 intermediate its ends, and the upper end thereof is bifurcated to provide the spaced portions or legs 26 and 27 between which is positioned a pulley 28 mounted upon a pin or trunnions 29. Guided for vertical movement within the slot 25 is a slide block 30, said block having a reduced portion 31 fitting within said slot. Arranged at the opposite side 105

of the channel iron is a plate 32 and extending through the slide block 30 and plate 32 is a bolt 33 having a nut 34 threaded upon the rear end thereof. Loosely mounted upon the bolt 33 forwardly of block 30 is a bell crank lever comprising a hub portion 35, through which said bolt 33 extends, and two arms 36 and 37 disposed at substantially right angles with respect to one another. The arm 36 of the bell crank lever carries at its outer end a roll 38 preferably of relatively hard rubber freely carried upon a pin 39 and provided with a plurality of grooves 40 within which the upper edges of the glass sheets 11 fit. These grooves are adapted to be in vertical alignment with the grooves in the surfacing wheel above which said roller is located.

The other arm 37 of the bell crank lever carries a weight 41 which is adjustable along the arm so as to vary the pressure of the roller 38 upon the upper edges of the glass sheets, said weight being preferably held in adjusted position by means of a set screw or the like 42. Thus, it will be readily apparent that the weight 41 normally tends to rock the bell crank lever upon bolt 33 to urge the roller 38 downwardly into engagement with the upper edges of the glass sheets. A stop 43 carried by slide block 30 is provided to engage arm 36 of the bell crank lever to limit downward movement of said roller.

As the glass sheets 11 are moved forwardly into engagement with a grinding or polishing wheel, the respective roller 38 engaging the upper edges of the sheets is adapted to maintain said sheets in a vertical position and also in engagement with the surfacing element. By passing the bolt 33 through the hub 35 of the bell crank lever, slide block 30 and plate 32, it will be readily seen that all of these parts can be properly secured together by a single fastening element and also secured to the vertical supporting arm 24 for vertical sliding movement with respect thereto. For instance, upon loosening the nut 34, the slide block, bell crank lever and roller can be raised or lowered as a unit and upon tightening of said nut, the above parts can be secured in the desired adjusted position.

Attached to the slide block 30 is one end of a cable 44 which runs upwardly over pulley 28 and has secured to its opposite end a balance weight 45 which is sufficiently heavy to counter-balance the roller 38 and associated parts during vertical adjustment thereof. With such an arrangement, it is possible for the roller 38 to be raised and lowered easily and quickly and with a considerably less degree of effort on the part of the operator than in the event no such counter-weight were used. Thus, after the nut 34 is loosened, the operator need simply exert a slight pull upon the cable 44 in the desired direction to effect the raising or lowering of the roller. Furthermore, the proper positioning of the roller can be more readily and conveniently effected.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In a machine for grinding an edge of a plate of glass, the combination of a grinding element having a groove formed in its periphery and adapted to partially support the glass on edge while being ground, supporting runways at

opposite sides of the grinding element cooperating therewith to guidingly support said plate of glass during grinding, a roller positioned above the plate and having a groove for receiving the upper edge of said plate therein, said roller being adapted to maintain the plate in a vertical position and in engagement with the grinding element, and means for adjusting said roller vertically.

2. In a machine for grinding an edge of a plate of glass, the combination of a grinding element having a groove formed in its periphery and adapted to partially support the glass on edge while being ground, supporting runways at opposite sides of the grinding element cooperating therewith to guidingly support said plate of glass during grinding, a roller positioned above the plate and having a groove for receiving the upper edge of said plate therein, said roller being adapted to maintain the plate in a vertical position and in engagement with the grinding element, means by which said roller may be adjusted vertically, and means for counter-balancing the roller during vertical adjustment thereof.

3. In a machine for grinding an edge of a plate of glass, the combination of a grinding element having a groove formed in its periphery and adapted to partially support the glass on edge while being ground, supporting runways at opposite sides of the grinding element cooperating therewith to guidingly support said plate of glass during grinding, a roller positioned above the plate and having a groove for receiving the upper edge of said plate therein, said roller being adapted to maintain the plate in a vertical position and in engagement with the grinding element, means for varying the pressure exerted by the roller upon the upper edge of the plate, and means for adjusting said roller vertically.

4. In a machine for grinding an edge of a plate of glass, the combination of a grinding element having a groove formed in its periphery and adapted to partially support the glass on edge while being ground, supporting runways at opposite sides of the grinding element cooperating therewith to guidingly support said plate of glass during grinding, a roller positioned above the plate and having a groove for receiving the upper edge of said plate therein, said roller being adapted to maintain the plate in a vertical position and in engagement with the grinding element, means for varying the pressure exerted by the roller upon the upper edge of the plate, and means for adjusting said roller vertically.

5. In a machine for grinding an edge of a plate of glass, the combination of a grinding element having a groove in its periphery and upon which the glass is partially supported on edge while being ground, supporting runways at opposite sides of the grinding means cooperating therewith to guidingly support the plate of glass during grinding, a fixed vertical support, a slide block carried by said support, a roller carried by said slide block and adapted to rest upon the upper edge of the plate and having a groove for receiving the said edge therein, a weight tending to normally urge the roller into engagement with the plate, and means for adjusting the roller, slide block and weight vertically as a unit.

6. In a machine for grinding an edge of a plate of glass, the combination of a grinding element having a groove in its periphery and upon which the glass is partially supported on edge while be-

- ing ground, supporting runways at opposite sides of the grinding means cooperating therewith to 5 guidingly support the plate of glass during grinding, a fixed vertical support, a slide block carried by said support, a roller carried by said slide block and adapted to rest upon the upper edge of the plate and having a groove for receiving the said edge therein, a weight tending to normally urge the roller into engagement with the plate, 10 means by which said roller, slide block and weight may be adjusted vertically as a unit, and means for counter-balancing the roller, slide block and weight during vertical adjustment thereof. 15
7. In a machine for grinding an edge of a plate of glass, the combination of a grinding element having a groove in its periphery and upon which the glass is partially supported on edge while being ground, supporting runways at opposite sides of the grinding means cooperating therewith to 20 guidingly support the plate of glass during grinding, a fixed vertical support having a vertical slot therein, a slide guided for vertical movement in said slot, a bell crank lever pivotally carried by said slide and including a pair of arms, a roller carried by one arm and adapted to rest upon the upper edge of the plate and having a groove for receiving the said edge therein, a weight carried by the other arm and acting to normally urge the roller into engagement with the glass plate, means 25 by which the bell crank lever and associated parts may be adjusted bodily vertically, and means connected with said slide for counter-balancing said bell crank lever and associated parts during vertical adjustment thereof. 30
9. In a machine for grinding an edge of a plate of glass, the combination of grinding means upon which the glass is partially supported on edge while being ground, means cooperating with the grinding means for guidingly supporting said plate of glass during grinding thereof, and pivotally mounted means engaging the upper edge of the glass plate for maintaining it in a vertical position and in engagement with the grinding means. 35
10. In a machine for grinding an edge of a plate of glass, the combination of grinding means upon which the glass is partially supported on edge while being ground, means cooperating with the grinding means for guidingly supporting said plate of glass during grinding thereof, and a pivotally mounted rotatable roll engaging the upper edge of the glass plate for maintaining it in a vertical position and in engagement with the grinding means. 40
